UNITED STATES PATENT OFFICE.

ROBERT H. MOORE AND MARGUERITE E. MOORE, OF NEW YORK, N. Y.

PASSENGER-CAR.

No. 840,704.

Specification of Letters Patent.

Patented Jan. 8, 1907.

Application filed April 19, 1906. Serial No. 312,733.

To all whom it may concern:

Be it known that we, ROBERT H. MOORE and MARGUERITE E. MOORE, citizens of the United States, and residents of No. 40 West Sixty-fifth street, in the city of New York, county of New York, and State of New York, have invented a new and useful Improvement in the Present Type of Passenger-Car, of which the following is a specification.

10 Our invention relates to the improvement on the present type of passenger-car; and the objects of our improvement are:

First. A continuous incoming and outgoing of passengers at the same time without interfering with one another's progress.

Second. It is an essential as a time-saver, especially during busy hours. (At present all passengers wishing to board a train or car are obliged to wait until the last passenger 20 leaving the car is off.)

Third. Trains arriving at a terminal, both doorways or passages may be used as exits, or the reverse.

We obtain these objects by the means illustrated in the accompanying drawings, in which—

Figure 1 is a side view of the end of a passenger-car with the doorways on it. Fig. 2 is a top view of the same passenger-car after the 30 removal of the roof.

Similar letters refer to similar parts throughout both the views.

a b on Figs. 1 and 2 indicate the doorways, by which passengers may be leaving the car 35 through a; while passengers wishing to board it are entering through b.

c indicates a partition in the center of the forward end and the center of the rear end of the car. One end of this partition terminates 40 on reaching the track or groove indicated by e.

d indicates a movable partition the use of which is to divide the incoming passengers, through b, from the outgoing passengers, through a, their course being directed by the partition c, which is at a right angle with it. 45

e indicates a track or groove on which d moves, which enables the doorways or passages a and b on the other side of the car to be used for a like purpose.

f indicates a doorway or passage. 50

g indicates windows.

We claim—

1. The combination, on a passenger-car, of an additional doorway or passage, to the doorway or passage now in use on both sides 55 of either end of a passenger-car, with a movable and a stationary partition communicating with the said doorways or passages, all substantially as set forth.

2. In a passenger-car, the combination of 60 an additional doorway or passage to the doorway or passage now in use on both sides of either end of passenger-car, with a movable partition communicating with the said doorways or passages, and vertically adjusted 65 on said track or groove, and capable of moving from one end of track or groove, to the other end of same.

3. The combination of a track or groove, with a movable and a stationary partition, in 70 conjunction with the two doorways or passages on both sides of either end of car, adapted for the purpose all substantially as set forth.

ROBERT H. MOORE.
